UNITED STATES PATENT OFFICE.

AUSTIN KIMBLE, OF WAUSAU, WISCONSIN, ASSIGNOR TO MARATHON ELECTRIC MFG. COMPANY, OF WAUSAU, WISCONSIN, A CORPORATION OF WISCONSIN.

INSULATED SQUIRREL-CAGE WINDING.

1,375,007.

Specification of Letters Patent. Patented Apr. 19, 1921.

Application filed May 12, 1919. Serial No. 296,648.

To all whom it may concern:

Be it known that I, AUSTIN KIMBLE, a citizen of the United States of America, and a resident of Wausau, county of Marathon, 5 and State of Wisconsin, have invented certain new and useful Improvements in Insulated Squirrel-Cage Windings, of which the following is a specification.

This invention relates to squirrel cage 10 windings, and rotor structures and methods of forming same. The main objects of the invention are to provide a squirrel cage rotor of simplified and more unitary character; to provide a simplified and better form 15 of squirrel cage winding; to provide improved means for insulating a squirrel cage winding from the core; to provide such a device adapted for efficient ventilation; to provide a squirrel cage in place on the core 20 in integral electrodeposit form; and to provide a method for forming and insulating a squirrel cage winding such as specified.

An illustrative embodiment of this invention is shown in the accompanying drawings, in which

Figure 1 is an end view partly in section, substantially on the line 1—1 of Fig. 2.

Fig. 2 is a longitudinal section on the line 2—2 of Fig. 1.

30 Fig. 3 is an enlarged sectional detail of one of the insulated bars in place in its slot.

Fig. 4 is an enlarged section across one of the core slots after the wax and black lead have been applied and preceding the electrodeposit step of the process.

In the construction shown in the drawings, the rotor 1 comprises a laminated core 2 mounted securely on the shaft 3 in any of the numerous approved ways understood 40 in the art. Said core is provided with a squirrel cage, including a peripheral series of bars 4 disposed in core openings or slots 5, and having their corresponding ends joined by rings 6. The squirrel cage is insulated from the core by a layer 7 of suitable dielectric material, preferably japan, which is adapted for ready application in accordance with the process hereinafter described.

50 The method of forming the rotor specified is as follows: The assembled slotted core 2 is first coated with wax as shown at 8, so as to protect the same from any electrodeposit of copper directly thereon. The wax is ap-

plied by rolling the core in hot wax. Powdered conducting material, such for instance as black lead shown at 9, is then applied to such parts of the core as are to receive the electrodeposit which is to form the squirrel cage, for which purpose it may be blown on 60 with an air brush. The black lead is applied to the interior of the slots 5, and to the peripheral zones 10 on the ends of the core connecting said slots, so that when the core is placed in the plating bath and the 65 electrolytic process is started, copper will be deposited as an integral layer, 4 and 6, lining the slots 5 and covering said end zones 10, whereby an integral hollow bar squirrel cage winding is formed in place on 70 the core.

The core slots 5 are so formed that when a sufficient thickness of copper has been deposited (say 1/16''), there will remain a central opening 11 in each bar 4 adapted to 75 enhance ventilation.

After the squirrel cage 4, 6 is formed, the rotor is heated and the wax 8 is blown out or otherwise removed, after which the core is placed in a receptacle containing japan 80 which replaces the wax, permeating all the interstices between the core and the electrodeposit. The core is then baked sufficiently to dry and harden the japan 7, whereupon as a result of said process the squirrel cage 85 is thoroughly insulated from the core and is held rigidly in place.

Although but one specific embodiment of this invention is herein shown and described, it is to be understood that numerous details 90 of the construction and process set forth may be altered or omitted without departing from the spirit of this invention as defined by the following claims.

I claim:

1. The method of forming a squirrel cage form of dynamo-electric device, which consists in coating a magnetic core with wax, then applying a coating of conducting material to the core over areas to be occupied by 100 the end rings and bars of the squirrel cage, then applying an electrodeposit of conducting metal to the coated areas, then removing the wax, and finally applying insulating material between the core and the electrode- 105 posit, in place of the wax removed.

2. The method of forming a squirrel cage form of dynamo-electric device, which con-

sists in coating a magnetic core with wax, then applying a coating of conducting material to the core over areas to be occupied by the end rings and bars of the squirrel cage, 5 then applying an electrodeposit of conducting metal to the coated areas, then heating the plated core and removing the wax, and

finally applying japan between the core and the electrodeposit in place of the wax removed.

Signed at Chicago this 9th day of May 1919.

AUSTIN KIMBLE.
